UNITED STATES PATENT OFFICE

ALEXANDER H. FRASER, JR., OF BROOKLYN, NEW YORK

AUDITORIUM SEAT

Application filed May 22, 1929. Serial No. 364,976.

This invention relates to foldable seats or chairs and is particularly adapted for use with seats in auditoriums, theatres, churches, schools and the like which are arranged in rows.

It very often is desirable to remove the seats from auditoriums and other halls to leave the floor space clear so that the space may be used for dances, banquets or for other purposes. For this purpose the seats should be capable of being removed from the floor space and replaced as quickly and easily as possible. When removed the chairs should be folded so that they will occupy the smallest possible space. It is also desirable at times to form aisles between the seats at various places and of various widths. However, the seats or chairs should be firmly constructed and held in fixed position when in place.

It is an object of the present invention to provide a novel construction for a row or rows of relatively folding seats such as that the seats may be quickly and easily folded into close proximity with other seats in the row.

Another object of the invention is to provide means by which the seats may be secured in place when in normal positions.

These and other important objects and features of the invention will appear from the following description of the preferred form of the invention illustrated in the drawings.

In the drawings—

Figure 1 is a diagrammatic side view of one construction embodying the present invention with the seats in open position and certain parts shown in section;

Figure 2 is a diagrammatic front view of the construction shown in Figure 1;

Figure 3 is a plan view of the construction shown in Figure 1 with certain parts shown in section;

Figure 4 is a detailed view in section of a preferred type of latching mechanism embodying details of the present invention;

Figure 5 is a plan view taken on the section line 5—5 of Figure 4;

Figure 6 is a side view of the construction

shown in Figure 1 with the seats folded, certain parts being shown in section;

Figures 7, 8 and 9 are views of details of the invention;

Figure 10 is a plan view of the seats in the folded position as in Figure 6, certain parts being shown in section; and

Figure 11 is a detailed plan view of the mechanism shown in Figure 5.

In the form of the invention illustrated in the drawings a plurality of similar seats are arranged in rows, one behind the other, each seat being formed of an upright member 2 which forms the back of the seat. The members 2 between laterally adjacent seats are T-shaped in cross section, whereas the corresponding members on the aisles or between independent longitudinal rows of seats are L-shaped in cross section. Seats 4 are pivoted to the upright members 2 by the hinges 5 and arms 6 which are U-shaped in cross section are also pivoted to the upright members by the hinges 7. Stanchions 8 formed of channel bars are pivotally connected to the outer ends of the arms 6 at the points 10 and are provided with supporting bars 12 against which the seats 4 rest when in their lowered positions. The stanchions 8 are pivotally secured at their lower ends to channel members 14 at the points 16. The members 14 are also pivotally secured to the uprights 2 at the points 18. Each of the seats in each row is connected to the seat directly in front thereof by the channel member 20 which is pivotally secured to the member 14 at the point 22 and to the upright 2 of the seat in front at the point 24. The articulated members 14 and 20 are U-shaped in cross section and connected so that one will fold into the other when the seats are folded.

This construction of the seats renders each seat foldable or collapsible so that it may be folded into a very small space and in close proximity to the seat directly in front thereof. When all of the seats of a row are folded together they take up positions as illustrated in Figure 6 with the arms 6 and seats 4 folded against the upright members 2 and with the stanchions 8 in folded

relation within the channeled portions of the arms. The connecting members 14 and 20 by which the lower ends of the stanchions 8 are connected to the upright members 2 of 5 each seat and to the seats in front are also folded into interfitting relation as indicated in Figures 6, 9 and 10.

The upright members of each seat are mounted upon rollers or casters 26 so that 10 the seats may be readily moved across the floor in folding the seats together. Any of the rows of seats may be folded in close proximity to the row of seats directly in front thereof, while the remaining seats 15 remain in their normal open position. If each longitudinal row of seats is independent of the laterally adjacent longitudinal rows of seats the seat may be folded while all of the remaining seats remain open.

20 In order to maintain the seats in their normal open position and in predetermined spaced relation one behind another in the row latching mechanism is provided which retains each seat in its open position and in 25 spaced relation to the other seats in the row. This latching mechanism is operable to release all of the seats and render them movable so that they may be folded merely by pushing the rear seats toward the front. 30 When it is desired to clear a hall for dancing or for any other purpose it is merely necessary to release the latch on the rear seat in the row and push the rear seat forward, thereby folding all of the seats in the row 35 into close proximity to each other and against the front seat or rail. Ordinarily the seats are arranged in transverse rows as well as in rows with one seat behind another and in this case the operation of a single 40 latching mechanism will release the latches on all of the seats in the longitudinal and transverse rows so that one or two attendants can push all of the seats forward into folded relation with the seats directly in 45 front in the longitudinal rows. In making aisles between the seats any number of independent longitudinal rows of seats may be folded by pushing the seats from the rear toward the seats in front until the aisle is 50 the length required.

The latch mechanism preferred is shown in Figure 5 as including a latch member 30 which engages under the lip 32 near the foot of the rearwardly-extending portion 34 of 55 the T-shaped upright member 2. The upright members at the ends of transverse rows of seats are L-shaped as illustrated at 36 in Figure 4. The lip 32 under which the latch 30 engages when in the latched position 60 preferably projects rearwardly of the portion 34 to provide sufficient clearance to permit the latch bar and housing, to be described, to be moved upwardly. A spring 38 bears against the latch member 30 to urge 65 it into the latching position and a member

40 limits the outward movement of the latch by engagement with an abutment 42 carried by the latch bar 44 and the spring 38.

A longitudinally-movable latch bar 44, located within the housing 46 in positioned 70 between the connecting articulated members 14 and 20 located on each side of each seat, as shown in Figures 3 and 4, and when latched will hold the members 14 and 20 in an aligned position by means of connectors 75 15 (Fig. 4) which connect the housing 46 to the articulated members 14 and 20 in a well known manner. The latch bar 44 is urged rearwardly in the housing 46 by means of a relatively strong spring 48 which bears 80 against the latch bar 44 and against an abutment 50 carried by the housing 46. The latch bar 44 is connected by a hinge 52 to a member 54 located near the base of the upright member 2 and formed with a projection 56 which extends through an opening 57 in the member 2 and to which the hinge 52 is connected. The rearward face of the member 54 is inclined to form a cam 58 engaging the beveled portion 59 at the end of the latch bar housing 46 as shown in Figure 5. The member 54 is also provided with a longitudinal slot 60 engaged by a pin 62 to guide the movement of the member 54 as it is moved forward or backward. The pin 62 85 is preferably the axle for the caster 26 which supports the upright member 2.

The last seat in the row is not provided with a member 54 but is formed with a member 64 having a projection corresponding to the projection 56 to which the hinge 52 for the last latch bar is secured. The member 64 is movable longitudinally with the latch bar 44 by means of an arm 66 engaging with the lug 68 on the member 64 and rotated by a 90 shaft 70 to which the arm 66 is secured.

The member 72 connected to the front seat or rail in the row is somewhat similar to the member 54 connected to the latch bar for each of the intermediate seats in the row. 100 This member is provided with a cam 58 for engaging the beveled end 59 of the latch bar housing 46 of the seat directly in the rear and is urged rearwardly by a spring 74 which bears directly against the upright member 2 of the front seat or against a 105 front rail.

The latch bar 44 and its housing 46 are located between the members 14 and 20 for laterally adjacent seats as illustrated in Figure 3, and foot boards 76 are carried by the members 20 on either side of the seat so that the members 20 and latch bar housings 46 do not project above the foot boards to trip the occupants of the seat as they pass between the seats in the transverse rows.

The operation of the latching mechanism is as follows:

When the seats are arranged as illustrated in Figure 1 and it is desired to release the 130

latch mechanism to permit the seats to be folded in close proximity to each other, the shaft 70 to which the arm 66 is secured is rotated to move the arm 66 rearwardly, thereby drawing the latch bar 44 and latch 30 which retains the last seat in the row in place rearwardly. As soon as the latch 30 is drawn rearwardly far enough to be disengaged from the lip 32 on the projecting portion 34 of the upright 2 of the seat directly in front thereof, the latch bar 44 for the next to the last seat is moved rearwardly by the strong spring 48 carried by the latch bar housing 46, thereby moving the member 54 rearwardly so that the cam 58 engages the beveled end of the latch bar housing 46 and raises the latch bar and latch above the lip 32. In a similar way the rearward movement of the latch bar 44 for the next to the last seat withdraws the latch 30 from the lip 32 which is carried by the upright 2 for the seat directly in front of the next to the last seat and the latch bar housing for this seat will also be raised by the member 54 for the seat directly in front thereof. In this way operation of the shaft 70 to withdraw the latch for the last seat in the row causes the latches for each of the remaining seats in the row to be released and each latch bar to be raised above the lip 32 carried by the upright member 2 of the seat directly in front.

In raising the latch bar 44 the alignment of the members 14 and 20 is broken and they are moved about their pivots by means of connectors 15 so that the stanchion 8 of each seat is raised upwardly and the hinge point 22 connecting the members 14 and 20 is raised sufficiently to permit the seats to be folded into close proximity to the seat in front merely by pushing on the rear seat.

In Figures 1, 2, 6, 7, 8 and 10 a front rail 82 is shown which may separate the seats from the orchestra in a theatre or be used in any other arrangement of the seats. An angle iron 84 is secured to the foot of the rail 82 and is provided with an opening in the horizontal portion thereof through which a securing member 86 extends. The member 86 is formed with projecting lugs 88 at its lower end which engage beneath a plate 90 secured to the floor. The plate 90 has an opening corresponding in shape to the lug 88 on the member 86 so that the member cannot be withdrawn when rotated to the dotted line position as shown in Figure 8. The upper end of the securing member 86 is formed with a thumb nut 92 against which a spring 94 bears to hold the member 86 in position.

In the preferred form of the invention illustrated and described laterally adjacent seats or rows of seats are connected by the T-shaped upright members 2. However, it may be desirable in some instances to form each row of seats independently of any

laterally adjacent seats or rows of seats whereas in other instances the seats may be joined laterally to any number of other seats. The seats may also be arranged in transverse rows and foldable against laterally adjacent seats instead of being arranged in longitudinally extending rows and foldable against the seats in front as in the preferred form illustrated and described. The invention therefore is not limited to its use with seats arranged in longitudinal rows or to longitudinal rows joined to laterally adjacent rows as illustrated in the form of the invention set forth above. Furthermore the invention is not limited to the particular form of folding seat or latching mechanism described except as defined by the claims.

What is claimed as new is:

1. The combination of a row of foldable seats, retaining means for each seat normally effecting the holding of said seats in one position, and means actuated by the release of one of said retaining means for releasing another of said retaining means.

2. The combination of a row of foldable seats located one behind another, retaining means normally associated with each seat holding said seats in spaced position, and means actuated by the release of one of said retaining means for releasing the retaining means normally holding the seat in front in open position.

3. A row of folding chairs comprising a plurality of chairs, the back legs of each being adapted for sliding support on a horizontal surface, arms of each chair being pivoted to the back and to the front legs thereof, and articulated spacing bars connecting the back legs of adjacent chairs, the front legs of each chair being pivoted to the spacing bar so as to be supported thereby and move therewith, and the seat of said chair being pivoted on the back and supported on the front legs so as to permit its being folded with or separately from the arms, front legs, and spacing bar.

4. The combination comprising a row of seats slidably supported, aligned articulated members connecting each two adjacent seats, latch means securing the articulated members in aligned position and holding the seats in a spaced relationship, and means for releasing the latch means, said latch means including means effective to break the alignment of said articulated members upon the release of said latch means.

5. The combination comprising a row of seats slidably supported, aligned articulated members connecting each two adjacent seats, latch means associated with each of the connected articulated members securing said members in aligned position and holding the seats in a spaced relationship, and means operative from a predetermined position for releasing certain of said latch means, said

latch means including means to release other of said latch means.

6. The combination comprising a row of seats slidably supported, aligned articulated members connecting each two adjacent seats, latch means securing the articulated members in aligned position and holding the seats in a spaced relationship, and means for releasing the latch means at an end of the row, 10 said latch means including means effective to break the alignment of said articulated members upon a release of said latch means.

7. The combination as defined in claim 4, 15 in which said latch means includes means operable at one position in the row of seats for breaking the alignment of said aligned articulated members at said one position in the row, and means operable with the aligned articulated members of each seat for 20 breaking the alignment of the articulated members of the next seat.

8. A row of folding chairs comprising a plurality of chairs, the back legs of each being adapted for sliding support on a horizontal surface, arms of each chair being pivoted to the back and to the front legs thereof, and aligned articulated members connecting the back legs of adjacent chairs, the front legs of each chair being pivoted to 25 the articulated members so as to be supported thereby and move therewith, the seat of said chair being pivoted on the back and supported on the front legs so as to permit its being folded with or separately from the 30 arms, front legs, and articulated members, means between each two adjacent seats for locking the articulated members in extended position, and means for successively releasing the locking means and for breaking the 35 alignment of the articulated members.

9. A row of folding chairs comprising a plurality of chairs, the back legs of each being adapted for sliding support on a horizontal surface, arms of each chair being pivoted to the back and to the front legs thereof, aligned articulated members connecting the back legs of adjacent chairs, the front legs of each chair being pivoted to the 40 articulated members so as to be supported thereby and move therewith, the seat of said chair being pivoted on the back and supported on the front legs so as to permit its being folded with or separately from the arms, front legs, and articulated members, 45 a spring latch operable with each pair of articulated members and adapted to lock the articulated members in their extended position, means tending to move the articulated members from their extended position sufficiently to break their alignment, and means 50 operable with the articulated members to effect the release of the next latch of the row.

10. A row of folding chairs comprising a plurality of chairs, the back legs of each being adapted for sliding support on a horizontal 55

surface, arms of each chair being pivoted to the back and to the front legs thereof, and aligned articulated members connecting the back legs of adjacent chairs, the front legs of each chair being pivoted to the articulated members so as to be supported thereby and move therewith, the seat of said chair being pivoted on the back and supported on the front legs so as to permit its being folded with or separately from the arms, front legs, and articulated members, 60 means between each two adjacent seats for locking the articulated members in extended position, and means for successively releasing the locking means and for breaking the alignment of the articulated members.

11. The combination comprising a row of seats slidably supported, aligned articulated members connecting each two adjacent seats, mechanism to effect a securing of the articulated members in aligned position to thereby hold the seats in a spaced relationship and to effect the release of the articulated members at will after being secured and to effect a breaking of the alignment of 70 said articulated members.

12. The combination comprising a row of seats slidably supported, aligned articulated members connecting each two adjacent seats, mechanism to effect a securing of the articulated members in aligned position to thereby hold the seats in spaced relationship and to effect the release of the articulated members from an end of the row of seats after being secured and to effect a breaking of the alignment of 75 said articulated members.

13. The combination as defined in claim 11, in which the said mechanism includes means operable from one position in a row of seats for breaking the alignment of said aligned articulated members at one position in the row, and means operable with the aligned articulated members of each seat for breaking the alignment of the articulated members of the next seat.

Signed at New York, New York, this 26th day of April, 1929.
